UNITED STATES PATENT OFFICE.

RUDOLPH KLANN, OF CHICAGO, ILLINOIS.

FLUSH VALVE.

Application filed June 6, 1925. Serial No. 35,450.

My invention relates to flush valves and has among its objects the production of a device of the kind described, which is simple, convenient, compact, efficient and satisfactory for use wherever found applicable. A particular object of the invention is to provide a flush valve having improved means for adjusting the valve with respect to the pressure in the system of which it forms a part. Another object of the invention is to provide a flush valve having improved means for re-filling a bowl or the like. A still further object of the invention is to provide a flush valve having improved means for regulating the quantity of water which will pass through the valve each time it is actuated. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a central longitudinal section through a flush valve embodying my invention, the valve being shown in connection with associated apparatus;

Figs. 2, 3 and 4 are sections taken on lines 2—2, 3—3 and 4—4, respectively, of Fig. 1; and

Fig. 5 is a fragmentary elevation of an apertured sleeve and parts carried thereby, the sleeve and said parts being shown in section in Fig. 1.

I prefer to disclose the present invention as it is embodied in a flush valve of the type described in my U. S. Letters Patent No. 1,507,383 dated September 2, 1924. In the drawings the improved valve is designated generally by the reference character 3 and is positioned between and operatively connected to a bowl 2 and a riser 1. The riser 1 connects the flush valve 3 to any suitable source of water under pressure, the riser being of the type usually employed in buildings and the like. The riser may, of course, be made of suitable proportions and may be connected to any desired number of valves 3. The valve 3 is connected to the bowl 2 by nipples 2^a and 2^b and an elbow 2^c but

any other suitable means may be substituted therefor.

The means for connecting the riser 1 to the valve 3 preferably comprises a T-fitting 1^a forming part of the riser and communicating through a nipple 1^b with a T-fitting 3^a, the T-fitting 3^a constituting the casing for the valve 3. Screw-threaded into the upper end of the T-fitting 3^a is a plug 3^b and screw-threaded into the lower end of the T-fitting 3^a is a plug 3^c into which is threaded the nipple 2^a. Arranged within the hollow interior of the T-fitting 3^a is a sleeve 8 which has one or more ports 9 of the desired size and shape intermediate its ends, these ports being preferably arranged adjacent the lower end of the sleeve. Circular plates 10 and 11, or the equivalent, are arranged transversely across the upper and lower ends, respectively, of the sleeve 8 and form a chamber 8^a within the sleeve. The ports 9 communicate with the chamber 8^a and the effective area of the ports may be controlled by means comprising an arcuate band 9^a rigidly secured to a plate 9^b mounted upon the sleeve 8 (Figs. 3 and 5). The upper and lower ends of the plate 9^b are slotted as at 9^c and 9^d, respectively, the slot 9^c accommodating a pin 9^e projecting from the sleeve 8 and the slot 9^d accommodating the shank of a screw 9^f threaded into the sleeve 8. Obviously, the plate 9^b and the arcuate band 9^a may be raised or lowered to uncover or cover the ports 9. The screw 9^f may be manipulated to secure the band 9^a in any adjusted position with respect to the ports 9. The arcuate band 9^a is preferably flexible and its inner surface is normally spaced from the outer surface of the sleeve 8 (Fig. 3). This construction permits water flowing under pressure from the nipple 1^b to collapse the band as the water passes into the ports 9. When the band 9^a is so collapsed the effective area of the ports 9 is reduced and less water will pass through the valve for each actuation thereof. In practice, the band 9^a is adjusted with respect to the pressure obtaining in the riser 1 but it will be readily understood that if this pressure increases in value within certain limits the band 9^a will automatically adjust itself with respect to the increase in pressure and prevent an undesirable amount of water from passing through the valve.

The plate 10 has a central port there-

through provided with a valve seat 12 at its inner side, the valve seat 12 being adapted to cooperate with a valve 13 having a stem 14 projecting upwardly through the plug 3^b. The plate 11 has a central discharge opening therethrough provided with a valve seat 15 at its inner side. A valve 16 normally engages the valve seat 15 to close the discharge opening. The valve 16 is provided with a tubular valve stem 16^a to which are rigidly secured two apertured disks 16^b and 16^c, the disks being spaced from each other and being concentrically disposed with respect to the tubular valve seat 16^a. A slight clearance is provided between the outer edges of the disks 16^b and 16^c and the inner surface of the sleeve 8 so that water entering through the inlet ports 9 may leak or flow upwardly past the disks to equalize the pressures obtaining within the chamber 8^a. This insures that the valve 16 will normally seat upon the valve seat 15.

The upper end of the valve seat 16^a is normally closed by a valve or plate 16^d which is maintained in operative relation with respect to the valve seat by a plurality of screws 16^e having hexagonal heads 16^f. As best shown in Fig. 1, the screws 16^e prevent the plate 16^d from moving transversely of the valve stem 16^a but permit a limited movement longitudinally thereof. Slidably mounted within the valve stem 16^a is a valve 17 arranged to cooperate with a valve seat 17^a formed on the inner end of a tubular stem 17^b threaded through the valve 16. Clearance is provided between the valve 17 and the inner surface of the valve stem 16^a so that water may leak or flow therebetween. A nut 17^c threaded on the tubular stem 17^b may be manipulated to lock the tubular stem in a plurality of adjusted positions with respect to the valve 16. It will be noted that the tubular valve stem 16^a is provided with a plurality of ports 16^g whereby water may flow from the ports 9 into the interior of the valve stem 16^a and thence through the tubular member 17^b.

Projecting into the plate 10 is a bore 10^a, which, at its inner end, communicates with the chamber 8^a, a valve seat 16^b being formed at this point. A conical valve 10^c formed upon a screw 10^d may be brought into a plurality of adjusted positions with respect to the valve seat. Obviously, water from the riser 1 may enter the chamber 8^a by way of the bore 10^a when the valve 10^c is unseated.

A relief duct 19 is arranged to extend through the plates 10 and 11, the upper end of the duct communicating with the space above the plate 10 and the lower end of the duct communicating with the discharge outlet leading to the bowl. Slidably mounted upon the duct 19 and disposed intermediate the disks 16^b and 16^c is a tube 19^a which

prevents an undesirable amount of water from flowing through the apertures which are provided in the disks to accommodate the duct.

The upper end of the valve stem 14 is secured in a button 20 which is slidably mounted upon the upper end of a tubular casing 21 enclosing the valve stem and threaded into the plug 3^b. A rubber tube 24 is interposed between the button 20 and the lowermost end of the tubular casing 21. The rubber tube 24 serves as a gasket and also yieldingly holds the valve 13 in engagement with the valve seat 12. When the button 20 is depressed the valve 13 will be unseated, the rubber tube being compressed. When the button is released the rubber tube will elongate to its normal length and retrieve the button and the valve 13 to their normal position. For ornamental purposes, I preferably provide a removable cap 25 at the upper end of the T-fitting 3^a, which cap 25 encloses the plug 3^b and the lower end of the tubular casing 21.

Assuming that the parts are in the positions wherein they are shown in Fig. 1 and that the riser 1 is connected to a suitable supply of water under pressure, it is obvious that the chamber 8^a and the tubular valve stem 16^a will be full of water. As above explained, equalized pressures will obtain throughout the chamber 8^a and within the valve stem 16^a. If the button 20 is then depressed the valve 13 will be unseated and water will flow from the chamber 8^a into the space above the plate 10. This water may escape to the bowl by way of the duct 19 and by way of the above described means connecting the valve 3 with the bowl. The pressures in the chamber 8^a will then be unbalanced and the valve 16 together with the parts carried thereby will move upward to the chamber 8^a. Practically simultaneously, the valve 17 will move upwardly relative to the valve stem 16^a and uncover the opening through the tubular stem 17^b, the plate 16^d being urged against the hexagonal heads 16^f of the screws 16^e. Water will then flow through the ports 9, the lower end of the chamber 8, the discharge opening in the plate 11 and thence to the bowl 2. When the button 20 is released, the valve 13 moves into engagement with the valve seat 12. The water entering through the ports 9 then leaks or flows upwardly through the space between the inner surface of the sleeve 8 and the outer edges of the disks 16^b and 16^c. This equalizes the pressure obtaining in the chamber 8^a and permits the valve 16 to return to its seat 15. This restoration of normal conditions in the chamber 8^a is also accompanied by a return of the plate 16^d to its seat upon the tubular valve stem 16^a. The water entering through the apertures 16^g equalizes the pressures obtaining within the

tubular stem 16^a with respect to the pressures obtaining in the chamber 8^a and permits the valve 17 to return to its seat 17^a. The arrangement is such that the valve 17 will remain unseated for a short interval of time after the valve 16 has engaged the valve seat 15. This permits a relatively small quantity of water to flow through the tubular stem 17^b to refill the bowl. The amount of water which passes through the tubular stem 17^b after the valve 16 has engaged the valve seat 15 may be regulated by manipulating the tubular stem 17^b. Thus, if the tubular stem 17^b is manipulated to project a greater distance into the tubular member 16^a the length of travel of the valve 17 will be shortened and less water will be supplied to refill the bowl 2. Obviously, the tubular member 17^b may be manipulated to lengthen the stroke of the valve 17 so as to increase the amount of water supplied to refill the bowl 2.

The aforementioned screw 10^d may be manipulated to increase or decrease the amount of water supplied to the bowl during the flushing operation. Thus, if the screw is manipulated to unseat the valve 10^c from the valve seat 10^b water may pass directly from the nipple 1^b to the chamber 8 by way of the bore 10^a. Then if the valve is actuated, normal conditions within the chamber 8 will be restored in less time than is the case when the valve 10^c is seated. The screw may be adjusted into any desired position with respect to the valve seat 10^b so that this return to normal conditions within the chamber 8^a will take place within a predetermined period of time and thus insure that the desired and proper amount of water will pass through the valve for each actuation thereof.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A device of the character described comprising a hollow member, a sleeve arranged in said hollow member, a closure member for each end of the sleeve having a port therethrough forming a valve seat, the sleeve having inlet ports adjacent the lower closure, a manually operable valve controlling the upper closure port, a second valve for controlling the lower closure port, said second valve having a chamber formed therein provided with a discharge opening, and a third valve disposed in said chamber for controlling said discharge opening.

2. A device of the character described comprising a hollow member, a sleeve arranged in said hollow member, a closure member for each end of the sleeve having a port therethrough forming a valve seat, the sleeve having inlet ports adjacent the lower closure, a manually operable valve controlling the upper closure port, a second valve having a chamber formed therein and adapted to control the lower closure port, said second valve being operable within the sleeve and of less diameter than the sleeve to allow water entering the sleeve inlet ports to pass therearound and into the space between the valves, said chamber being provided with a discharge opening, and a third valve disposed in said chamber for controlling said discharge opening.

3. A flush valve comprising a chamber having a discharge opening at one end thereof and having a second discharge opening at the other end, valves for controlling said discharge openings, ports communicating with said chamber, means connecting said ports with a supply of liquid under pressure, and a flexible band around said chamber and collapsible under fluid pressure for controlling the flow of liquid through said ports.

4. A flush valve comprising a chamber having a discharge opening through each end, a manually operated valve controlling the passage through the discharge opening at one end, a pressure operated valve controlling the discharge through the opening at the other end of the chamber, ports communicating with said chamber, means for connecting said ports with a supply of liquid under pressure, and a flexible band around said chamber and collapsible under fluid pressure for controlling the flow of liquid through said ports.

5. A valve of the character described including a chamber having a discharge opening at each end, a manually actuated valve controlling the passage through one of said discharge openings, a pressure operated valve controlling the discharge through the other opening, a tubular valve stem carried by the pressure controlled valve, a valve movable in said stem, a tubular member carried by the pressure controlled valve and communicating with said tubular valve stem with the passage therethrough controlled by the movement of the float valve, ports communicating with the chamber, means connecting the ports with a supply of liquid under pressure, and a flexible band around said chamber and collapsible under fluid pressure for controlling the flow of liquid through said ports.

In testimony whereof, I have hereunto signed my name.

RUDOLPH KLANN.
